UNITED STATES PATENT OFFICE.

M. RICHARDS MUCKLE, JR., OF PHILADELPHIA, PENNSYLVANIA.

MAN-HOLE CHAMBER FOR UNDERGROUND ELECTRICAL CONDUITS.

SPECIFICATION forming part of Letters Patent No. 378,802, dated February 28, 1888.

Application filed November 23, 1887. Serial No. 255,978. (No model.)

To all whom it may concern:

Be it known that I, M. RICHARDS MUCKLE, Jr., a citizen of the United States, and a resident of Philadelphia, Pennsylvania, have invented certain Improvements in Man-Hole Chambers for Underground Electrical Conductors, of which the following is a specification.

My invention consists of certain improvements in the man-hole structure for underground electrical conduits shown and described in my application for patent filed August 26, 1887, Serial No. 247,929, the main objects of my present invention being to strengthen the casing of the distributing-chamber, to provide for the proper protection of the wires and connections in said distributing-chamber, to facilitate the making of connections, to prevent the access of surface water to the man-hole chamber while work is being carried on therein, and to prevent the accumulation in the distributing-chamber of moisture due to sweating of the metallic casing of said chamber.

In the accompanying drawings, Figure 1 is a transverse section of a man-hole chamber for underground electrical conduits constructed in accordance with my invention, the chamber being closed. Fig. 2 is a similar view showing the chamber open and one of the cover-plates of the distributing-chamber removed for permitting access to the wires and connections therein. Fig. 3 is a sectional plan view through the distributing-chamber of the man-hole structure; and Fig. 4 is a transverse section of the distributing-chamber with its cover-plates entirely removed, and showing various connections in said chamber.

As in the application above referred to, A represents the brick or masonry work, which lines the lower portion of the man-hole chamber of an underground electrical conduit, D' being the supporting structure for the man-hole cover-plate, and F an intervening casing inclosing a distributing-chamber extending completely around the man-hole chamber and extending laterally outward therefrom, this casing having in its outer wall openings for the reception of various branching conduits, each composed of a series of tubes confined closely together, four of these conduits being shown in the present instance. It is of great practical

importance that the access of moisture to this distributing-chamber shall be absolutely prevented, as there is always more or less naked 55 conducting-surface exposed in the distributing-chamber, and the access of moisture thereto would cause a constant leakage of current.

The inner side of the casing F is open all around, but has at top and bottom projecting 60 flanges a, the upper edge of the lower flange being rounded and the lower edge of the upper flange being beveled, with the bevel toward the inside of the chamber. To each side of the casing is fitted a closing-plate, G, the 65 under face of which is rounded to accord with the rounded upper edge of the lower flange of the casing, while the upper edge of the plate is beveled to correspond with the beveled lower edge of the upper flange thereof, and 70 suitable packing-gaskets are interposed between both the upper and lower edges of these closing-plates and the adjacent edges of the flanges of the casing. The meeting corners of the closing-plates are likewise beveled 75 and provided with packing-gaskets, as shown in Fig. 3. To suitable openings formed in the upper flange a of the casing are adapted clamp-bolts b, which are provided with nuts bearing on the outer face of the flange, the 80 clamp-bolts acting upon the inner face of each of the closing-plates at and near the upper edge of the same. It will thus be seen that by tightening the nuts on these clamp-bolts the beveled faces of the closing-plates and of the 85 upper flange of the casing will be drawn firmly together, thus not only insuring a tight joint at that point, but also forcing the closing-plates downward and insuring an equally tight joint at their lower edges, while at the same time 90 the beveled corners of the closing-plates are drawn together, and tight joints thus insured at those points. Having once been applied and properly fastened, these closing-plates will not thereafter be disturbed in the ordinary use 95 of the man-hole chamber, the plates thus forming practically the inner wall of the casing F and constituting the same a box-girder, which is amply strong enough to withstand any crushing strain to which it may be subjected 100 by reason of heavy loads passing over the top of the structure.

Access to the distributing-chamber is had through openings in the closing-plates, which

openings are provided with cover-plates *H*, resting at their lower edges in suitable pockets, *e*, formed on the closing-plates, the cover-plates being secured, under ordinary circumstances, by means of clamps *d*, carried by bolts which pass through the flanges of the casing *F*, these clamps being operated by handled nuts *f*, so that the inner faces of the cover-plates may be pressed firmly against the outer faces of the closing-plates around the openings therein, and a tight joint between the two thus maintained. On removing the clamps, however, the cover-plates may be swung downward and outward, the construction providing for the pivoting of said plates at their lower edges, and when the plates are thus depressed, or after the plates have been removed, free access can be had to all parts of the distributing-chamber; or, when access to but one part of the same is desired, but one of the plates may be removed, as will be readily understood.

In order to still further protect the distributing-chamber, I insert between the top of the casing *F* and the masonry above the same the upper edge of a protecting-sheet, *I*, of oil-cloth, rubber, or other water-proof material, which extends completely around the man-hole chamber, and when the man-hole is closed hangs down over the closing-plates and their covers, as shown in Fig. 1, and prevents the access to said closing-plates and covers of any water that may leak into the man-hole chamber around the cover-plate. When the man-hole chamber is open, this protecting-sheet is drawn upward and spread outward above the top of the man-hole, so that it receives and retains any surface water that would otherwise flow down the sides of the man-hole chamber and, by wetting the hands or arms of the man making the connections, increase the risk of accident.

In the device described in my former application it was proposed to carry the wires or cables themselves around the distributing-chamber from one conduit to another; but in the present device I provide the distributing-chamber with a series of conducting-rods, *g*, suitably supported therein by insulated hangers *h*, the connections being made between these conducting-rods and the wires where the latter enter the distributing-chamber from the conduit. For instance, in Figs. 1 and 2 I have shown two wires so connected.

When a line is to be taken from the man-hole chamber to a neighboring building, I provide the connections between the rods *g* and the branch line with suitable cut-out plates, *i*, provided with the usual circuit-closing plugs, on withdrawing which the current is cut off from the building, the current being re-established on again inserting the plugs. I also provide in each distributing-chamber a converter, *M*, which is supplied with current from the rods *g* through the medium of branch wires *m m'*, the induced current being carried by wires *m'* to a lamp, *K*, located in the dis-

tributing-chamber, whereby the proper lighting of the latter is provided for in cases where the natural light is not sufficient.

70

The distributing-chamber has wood lining-strips similar to those of the chamber shown in my above-mentioned application; but on the inner side of the casing *F* are formed supporting ribs or lugs *n*, which prevent the contact of the wood lining-strips with the casing, a chamber, *s*, being thus formed between the casing and the wood lining, and openings *p* being formed in the lower flange *a* of the casing, so that any moisture which collects in the chamber between the casing and its lining—such, for instance, as might be caused by the sweating of the casing—will flow to the bottom of the casing and escape through these openings into the man-hole chamber, the supporting ribs or lugs being recessed in such manner that moisture can find its way from any portion of the casing to one or other of the outlet-openings. (See dotted lines, Fig. 3.)

85

I do not in this application claim a distributing-chamber, extending around the man-hole chamber and having its inner side closed by detachable plates, as this forms part of the subject-matter of a separate application filed by me on the 26th day of August, 1887, Serial No. 247,929.

90

What I claim in my present application, and desire to secure by Letters Patent, is—

95

1. The combination of the casing of a distributing-chamber, extending around the man-hole chamber and communicating with the conduits, with plates closing the openings around the inner side of the casing, said closing-plates having openings provided with detachable cover-plates, all substantially as specified.

100

2. The combination of the casing of the distributing-chamber, having an opening around the inner side, closing-plates constructed to form overlapping joints with the casing and with each other, and clamps for drawing these joints together, all substantially as specified.

105

3. The combination of the casing of the distributing-chamber, having an opening around its inner side, with closing-plates forming a rounding joint at the bottom of said opening and a beveled joint at the top of the same, all substantially as specified.

110

4. The combination of the distributing-chamber, and the closing-plates around the inner side of the same, with a protecting-sheet extending around the man-hole chamber and secured above the casing of the distributing-chamber, whereby it is adapted to cover and protect the closing-plates, all substantially as specified.

115

5. The combination of the casing of the distributing-chamber, and closing-plates around the inner side of the same, with a protecting-sheet extending around the man-hole chamber and secured above the casing of the distributing-chamber, said sheet being such that it can be drawn up above the mouth of the man-hole chamber, all substantially as specified.

120

125

130

6. The combination of the casing of the distributing-chamber, the wood lining applied thereto, and the intervening drainage-space having outlet-openings, all substantially as specified.

7. The combination of the distributing-chamber with conducting-rods supported therein, and providing the means of connection between the conductors of the different conduits, all substantially as specified.

8. The combination of the distributing-chamber, the conduits, conductors therein, the con-

ducting-rods extending around the distributing-chamber, and cut-outs in the connections between the rods of the distributing-chamber and conductors in the conduit, all substantially as specified. 15

In testimony whereof I have signed my name to this specification in the presence of two subscribing witnesses.

M. RICHARDS MUCKLE, JR.
